UNITED STATES PATENT OFFICE.

JAMES P. MADDEN AND CARL G. NORDSTROM, OF BETHLEHEM, PENNSYLVANIA,
ASSIGNORS TO BETHLEHEM STEEL COMPANY.

SIX-WHEEL TRUCK.

Application filed January 13, 1928. Serial No. 246,401.

Our invention relates to improvements in railway trucks and more especially to trucks of the six-wheeled type.

One of the objects of our invention is to provide a six-wheeled truck construction for locomotive tenders suitable for the application of an auxiliary locomotive in which the application of the load upon the axles is more equally distributed between the three axles. 10 Another object of our invention is to form a spring support between the rear two axles so that the central portion of the truck frame at this point will be more fully sustained and resiliently supported along the center line of 15 the truck.

With these objects in view our invention consists in the construction and novel combination and arrangement of parts, herein-after more fully described and illustrated in 20 the accompanying drawings and pointed out in the claims hereto appended.

Having thus given a general description of our invention, we will now in order to make the same more clear, refer to the accompanying 25 two sheets of drawings in which like characters of reference indicate like parts:

Fig. 1 is a top plan view of a six-wheeled truck showing a portion of the truck frame broken away to more clearly illustrate the 30 application of our invention;

Fig. 2 is a side elevation of the truck shown in Fig. 1;

Fig. 3 is a vertical transverse sectional elevation taken on the line III—III of Fig. 2; 35 and

Fig. 4 is a detail perspective view of one of the swing-hangers.

Referring now to the characters of reference on the drawings: the numeral 1 indicates 40 the truck frame as a whole preferably of integral cast construction, comprising spaced side frames or wheel pieces 2 having downwardly extending jaws of aligned pairs of pedestals 3, 4 and 5. The wheel pieces 2 are 45 integrally connected together at their forward ends by means of a tie bar 6, and centrally by means of an H shaped bolster member 7, comprising a center plate bearing portion 8 having outwardly extending side bearings 9 and front and rear transoms 10 and 11 respectively all of which are formed integral with the wheel pieces. The transoms 10 and 11 are of hollow box section and are connected to center plate bearing portion 8 by means of 50 span webs 12 and 13. The aligned pairs of 55

pedestals 3, 4 and 5 are adapted to receive bearing boxes 14, 15 and 16 in which are journaled the ends of the axles 17, 18 and 19 respectively. 20 indicates equalizer bars mounted in pairs one on each side of the 60 wheel pieces. These equalizer bars are of U-shaped construction having horizontal ends 21, offset as at 22, to engage sockets 23 and 24 formed on top of the journal boxes for the axles 17 and 18. The equalizer bars are connected together centrally by means of spring seat plates 25, for receiving helical springs 26, which are interposed between spring sockets 27 formed on the under side of the wheel pieces between the pedestals 3 and 4 70 at the ends of the transom 10.

In order to apply an auxiliary locomotive to a six-wheeled truck, between a pair of axles, it is necessary that two of the axles should be spaced apart far enough to accommodate the engine and frame. In order to conform with conventional practice with regards to the spacing of the outer axles, it is necessary to have the other or intermediate axle spaced fairly close to one of the end or outer axles. 75

With the type of locomotive auxiliary propulsion device it is proposed to mount on a truck of the class shown in this application the forward portion of the auxiliary engine 85 frame will be supported by bearings (not shown) mounted on each side of the gear 28 on the axle 17, while the rear portion of the auxiliary engine frame will be suspended from the link 29 pivotally secured to the span 90 web 12.

As the major portion of the weight of the auxiliary engine is sustained by the link 29 and the entire weight of the body of the locomotive tender is received upon the center 95 plate, it is desirable to more fully support the central rear portion of the truck frame. To this end we form a resilient support for the rear central portion of the bolster comprising a spring plank 30 extending transversely 100 of the truck between the center and rear axles of the truck, having its ends formed with grooved sockets 31 for engaging swing-hangers 32 which are each pivoted by means of pins 33 to an equalizing device, each comprising a pair of yokes 34 mounted on either side of the wheel pieces. The central portions of the yokes 35 are offset as at 36 to engage sockets 37 formed in the tops of the journal boxes 16 of the rear axle 19. The opposite ends of 110

- the yokes are secured by means of pins 38 to spring seat plates 39 for receiving helical springs 40 which are interposed between the spring sockets 41 in the rear ends of the wheel pieces of the truck frame and the spring plates. The spring plank 30 is of I-beam cross section and bowed downwardly at the central portion, the flanges at the central portion being of greater width than at the ends.
- 10 The upper central portion is formed with spring seats 42 for receiving helical springs 43 which are interposed between the spring sockets 44 formed on the under face of the transom 11 and the spring seats 42.
- 15 In supporting the rear central portion of the truck in this manner we are able to equalize and distribute the weight of the truck on the springs to a much greater advantage than has been obtained heretofore.
- 20 Although we have shown and described our invention in considerable detail, we do not wish to be limited to the exact and specific details shown and described, but may use such substitutions, modifications or equivalents thereof as are embraced within the scope of our invention or as pointed out in the claims.
- Having thus described our invention what we claim and desire to secure by Letters Patent is:
1. In a car truck, comprising side frames, a bolster having spaced transoms connecting the side frames, a spring-plank mounted below one of the transoms, and springs mounted on the spring-plank for supporting the transom.
2. In a car truck, comprising spaced wheel pieces, a bolster connecting the wheel pieces, a spring-plank mounted between the central and one of the end axles of the truck, a transom connecting the wheel pieces together above the spring-plank, and springs mounted on the spring-plank for supporting the transom.
3. In a six-wheeled truck, comprising spaced wheel pieces, a transom connecting the wheel pieces together, a spring-plank mounted below the transom, and springs mounted on the spring plank for supporting the transom.
4. In a six-wheeled truck, comprising spaced wheel pieces, a transom rigidly connecting the wheel pieces together, a spring-plank movably mounted below the transom, and springs interposed between the transom and spring-plank for supporting the transom.
5. In a six-wheeled truck, comprising spaced wheel pieces, a transom connecting the wheel pieces together, a spring-plank having its ends mounted in swing-hangers below the transom, and springs interposed between the transom and spring-plank at an intermediate point for supporting the transom.
6. In a six-wheeled truck, comprising spaced wheel pieces, a transom formed integral therewith connecting the wheel pieces together, a spring-plank mounted below the transom, swing-hangers resiliently mounted on each side of the truck for supporting the ends of the spring-plank, and springs interposed between the transom and spring-plank at an intermediate point for supporting the transom.
7. In a six-wheeled truck, comprising spaced wheel pieces having pedestals formed thereon, a transom connecting the wheel pieces together, at a point between one of the outer axles and intermediate axle, journal boxes carried by the jaws of the pedestals, yokes extending over the journal boxes for the end axle having their central portions bearing thereon, means for resiliently holding the outer ends of the yoke, swing-hangers attached to the opposite ends of the yokes, a spring-plank beneath the transom having its ends supported by the swing-hangers, and springs interposed between the spring-plank and the transom.
8. In a six-wheeled truck, comprising spaced wheel pieces having pedestals formed integral therewith, journal boxes mounted between the pedestals, a transom rigidly connecting the wheel pieces together at a point between one of the outer axles and intermediate axle, yokes arranged in pairs on each side of the wheel pieces extending over the journal boxes of the outer axle and engaging therewith, a spring-plate pivotally attached to the outer ends of each pair of yokes, springs interposed between the spring-plate and the wheel pieces, a swing-hanger pivotally connected between the opposite ends of the yokes, a spring-plank having its ends mounted in the swing-hangers, and springs interposed between the spring-plank and the transom.
9. In a six-wheeled truck, comprising spaced wheel pieces having pedestals formed integral therewith, journal boxes mounted between the jaws of the pedestals, a transom connecting the wheel pieces together at a point between one of the outer axles and intermediate axle, a pair of sockets formed in the tops of each of the journal boxes for the outer axle, said sockets being located one on each side of each wheel piece, yokes each having an offset central portion for engaging the sockets of the journal boxes arranged in pairs one on each side of the wheel pieces, a spring-plate pivotally attached to and connecting together the outer ends of each pair of yokes, springs interposed between the spring-plates and the wheel pieces, a swing-hanger pivotally connected between the opposite ends of each pair of yokes, a spring-plank having its ends formed with socketed grooves for engaging the swing-hangers, and springs interposed centrally between the spring-plank and the transom.
10. In a six-wheeled truck, comprising

- spaced wheel pieces having downwardly extending pedestal jaws formed integral therewith, a transom formed integral with the wheel pieces for connecting the wheel pieces 5 together at a point between one of the outer axles and intermediate axle, journal boxes carried by the jaws of the pedestals, sockets formed in the top of each journal box, yokes extending over the journal boxes for the end axle 10 having their central portions offset to engage the sockets formed in the top of the journal boxes, spring-plates attached to the outer ends of the yokes, springs interposed between the spring-plates and the wheel pieces, swing-hangers attached to the opposite ends of the yokes, a spring-plank mounted beneath the transom having its ends supported by the swing-hangers, and springs interposed between the spring-plank and the transom. 15
- 20 11. In a six-wheeled truck, comprising spaced wheel pieces having downwardly extending pedestal jaws formed integral therewith, a transom formed integral with the wheel pieces for connecting the wheel pieces together at a point between one of the outer axles and intermediate axle, journal boxes carried by the jaws of the pedestals, sockets formed in the top of each journal box, on either side of the wheel pieces, yokes extending over the journal boxes for the end axle 25 arranged in pairs one on each of the wheel pieces each having their central portions offset to engage the sockets formed in the top of the journal boxes, a spring-plate pivotally connecting the outer ends of each pair of yokes below the wheel pieces, springs interposed between the spring-plates and the wheel pieces, swing-hangers pivotally connecting the opposite ends of each pair of yokes, a spring-plank mounted beneath the transom 30 having its ends formed with grooved sockets for engaging the swing-hangers, and springs interposed between the central portions of the transom and spring-plank.

In testimony whereof we hereunto affix our signatures.

JAMES P. MADDEN.
CARL G. NORDSTROM.
